UNITED STATES PATENT OFFICE.

FREDERICK C. PERREM, OF BLACKROCK, IRELAND.

ELECTRICAL VIBRATOR.

Application filed June 2, 1925. Serial No. 34,349.

- This invention relates to a vibrator that is adapted alternately to make and break an electrical circuit at a rapid rate, and especially to such an apparatus used in conjunction with an inductive apparatus to produce high tension electricity. Such high tension current is useful for example for supplying the ignition circuit for an internal combustion engine.
- 10 One such form of interrupter is disclosed and claimed in a copending application, filed Feb. 25, 1921, in my name, having Serial Number 447,841. My present invention is in the nature of an improvement over the structure shown in this prior application.
- 15 It is another object of my invention to make it possible to install the apparatus with minimum difficulty, and to inspect the vibrator contacts readily.
- 20 It is another object of my invention to improve the operation of such devices, as well as to render their construction inexpensive and reliable.
- 25 My invention possesses other advantageous features, some of which with the foregoing, will be set forth at length in the following description, where I shall outline in full that form of my invention which I have selected for illustration in the drawings accompanying and forming part of the present specification. Although I have shown in the drawings but one form of my invention, I do not desire to be limited thereto, since the invention as defined in the claims may be embodied in other forms also.
- 30 Referring to the drawings:
- Figure 1 is a front view of an apparatus embodying my invention, and showing a casting for enclosing the associated parts;
- 35 Fig. 2 is a side view of the apparatus of Fig. 1, showing the manner of its support, for example on the dash of an automobile;
- 40 Fig. 3 is an enlarged sectional view of the evacuated tube in which the contacts are enclosed; and
- 45 Fig. 4 is an enlarged section of a detail.
- One of the important advantages of my invention resides in the ease with which the entire vibrator mechanism can be installed.
- 50 Thus in Figs. 1 and 2, I show a box 11 which encloses some of the vibrator mechanism. The box 11 has a top or cover 12 which is hinged at one edge to the upper edge of box 11, and has an open side, as clearly disclosed in Fig. 1. On top of box 11 there is supported, in the manner to be hereinafter described, a tube 13, enclosing the vibrator contacts. The cover 12 is arranged to provide a shelter for this tube, and in order to prevent the cover from being accidentally jarred open, a spring clasp 14 is provided on one end of box 11. This clasp has an aperture cooperating with the head 15 of a screw fastened into the end of the cover 12.
- 55 On the front of box 11, there are a pair of binding screws 16 fastened in, which serve as external terminals for the entire vibrator. Each binding screw has a thumb nut 17 by the aid of which the connections can be fastened.
- 60 The entire box 11 can be held in place on a stationary element 18 (Fig. 2) as by the aid of screws 19, passing through one side 20 of an angle member 10 fastened to box 11.
- 65 In order to hold the tube 13 in place in such manner that it can readily be detached and replaced, I provide a pair of spring clips 21, one near each end of the box 11. Each clip serves also as a means for conducting current to the tube parts, and is adapted to coact with the tube by resiliently gripping the extensions 22 provided at the tube ends. Each of the clips 21 also has an enlarged base 23 by the aid of which it may be 70 fastened to the top of box 11. It is evident that the entire tube can be taken off by simply pulling upwardly thereon; and, similarly, it may be reinserted or replaced by pressing it into place.
- 75 As explained in detail in my earlier application, the vibrator is used to open and close a circuit at a rapid rate, such as that of a coil which is supplied with low tension direct or low frequency alternating current. Due to the rapid fluctuation in current flow brought about by this make and break, there is a corresponding rapid fluctuation in the magnet field produced by the coil. In order to produce a high tension current, therefore, it is merely necessary to provide a coil of many turns which are interlinked with the fluctuating magnetic field. This secondary coil can then be used to supply the ignition current of an internal combustion engine. All this is now well-known, and has been 80 reviewed herein only for the purpose of elucidating the functions of the parts now to be described.
- 85 Since the opening and closing of the con-

- 110

tacts take place at a very rapid rate, severe 5 sparking would undoubtedly result without taking some precautions. Thus I find that the contacts do not spark injuriously when 10 enclosed in a vacuum, such as exists in an evacuated tube 13. Another important feature is to provide a condenser across the contacts to absorb the current induced in the primary circuit as the contacts open. It is 15 necessary to influence the contacts electromagnetically so that they will be opened by magnetic force, and this is usually done by providing an electromagnet and an armature, which latter carries one of the contacts. 20 As the electromagnet is in series with the contacts, it is evident that the desired rapid operation of the contacts can be secured by arranging the electromagnet in such manner that when energized it opens the contacts, 25 and when deenergized due to this opening, it permits the contacts to reengage. In this instance, in order to make it possible to enclose the contacts in tube 13, the armature of the electromagnet is likewise enclosed, 30 and is influenced by the electromagnet through the walls of the tube.

The electromagnet is shown diagrammatically at 24 in Fig. 3, and has a pair of poles 25 which are arc shaped to fit the tube 30 13. The magnet structure is located in the box 11, except for a flange 26 which is fastened to the top of box 11, and for these poles which project through the flange 26.

The vibrator contacts are most clearly 35 closed in Fig. 3, which shows the tube 13, preferably of glass, in section. At each end of the tube, there is a conducting cap 27 or 28, with which the extensions 22 are integrally formed. The cap 27 has a depending 40 foot 29 arranged to rest on top of box 11, and provided for the purpose of ensuring that the angular position of tube 13 will be correct as regards the pole pieces 25. The ends of tube 13 can be hermetically sealed 45 into the caps 27 and 28, as by the aid of wax, but of course some arrangement must be provided in addition to permit evacuation of the tube after the contact parts are all 50 assembled therein.

Each of the caps 27 and 28 serves as a 55 supporting medium for the contacts. For this purpose each is provided with a central projection such as 30, or 31, which extends toward the tube interior, and has a central threaded bore 32. A supporting post 33 is fastened into the bore 32. It has a disc-like head 34 to which other elements are fastened as by screws. Thus a doubled metallic element 35 is fastened to the right hand post 33, and serves as a support for 60 the contact spring 36. This spring is fastened to the lower portion of element 35 as by the aid of clamping plates 37 and 38 and the small screws 39. At its free end,

the spring 36 is hooked to serve as a stop 65 for the free end of the contact carrying spring 40. This is fastened to an intermediate portion of the main spring 36, and carries a contact 41 of tungsten or the like. Furthermore, spring 36 carries near its free 70 end, a looped piece 42 of magnetic material (Fig. 4) which serves as the armature for magnet 24. The spring 36 is so biased that the contact 41 touches a stationary contact 43 while magnet 24 is deenergized, but when 75 the magnet is energized, it attracts the armature 42 and thus pulls the contact 41 clear of contact 43. The hook 44 at the end of spring 36 serves to limit the relative movement of the two springs 36 and 40, and thus 80 to ensure ultimate opening of the contacts.

The stationary contact 43 is adjustable along its axis, and is for that purpose fastened to the end of a screw 45 which taps in a check nut 46 having a knurled head. This nut has external threads engaging the support 47 fastened to the post 33. An extension 48 is provided for the support 47, and a piece of insulation 49, such as glass, ties the two supports 35 and 47 together. In 90 this manner, considerable rigidity is imparted to the structure. Clamping plates 50 and 51 are provided for holding the glass 49 in place. Small screws 52 tap into parts 35 and 48, and pass through the insulation 49 to secure the clamping plates 50 and 51 in place.

In Fig. 3, I also indicate in general the wiring for the complete vibrator. This includes a condenser 53, which is located in 100 box 11, together with the coil 24. This condenser is connected across the two clips 21, whereby it connects, by way of caps 27, 28, and posts 33, to the stationary and movable contacts 43 and 41. One clip 21 is also directly connected to one of the posts 16. The other clip connects to one terminal of coil 24, the other terminal of which is connected 105 to the remaining post 16.

It is evident that when an external circuit, 110 including a source and the primary of an inductor coil, be connected in series across terminals 16, the first result would be energization of magnet 24, then retraction of 115 contact 41, which opens the magnet circuit, then reestablishment of the contact due to the deenergization of magnet 24. The cycle then repeats; and it is completed at a very rapid rate. There is thus an alternate opening and closing of the contacts 41 and 43. 120 Due to the fact that the condenser 53 is connected across the contacts, and that they are enclosed in an evacuated vessel, no serious 125 sparking results. Furthermore, since tube 13 is made from glass, the contacts can be observed readily. The entire tube can be removed should it ever be necessary, and can be replaced by a new tube, with facility.

The device is very compact and of such rugged structure as to ensure a relatively long life.

I claim:

- 5 1. In an electrical vibrator, a casing, an electromagnet in said casing having a pole piece projecting outside of the casing, an enclosed vessel, vibratory contacts in said vessel, an armature mechanically connected 10 to one of said contacts and also enclosed in the vessel, said armature coacting with the projecting pole piece, and means for holding the vessel on the casing in such position that the electromagnet can influence the armature, said means also serving as a connection to the contacts in the tube.
- 15 2. In an electrical vibrator, a casing, an electromagnet in said casing having a pole piece projecting outside of the casing, an enclosed vessel, vibratory contacts in said vessel, an armature mechanically connected to one of said contacts and also enclosed in the vessel, conducting caps at the ends of the vessel, connected to the contacts, and spring 20 clips on the casing for holding the vessel in proper position on the casing so that the electromagnet can influence the armature.
- 25 3. In a device of the class described, a pair of contacts adapted to make and break 30 an electrical circuit, an elongated mounting to which said contacts are secured in co-op-

erative relationship, a tubular vessel surrounding said contacts and having open ends, a conductor cap enclosing one end of said vessel and secured to one end of said mounting, said cap being electrically connected with one of said contacts, a second conductor cap enclosing the other end of said vessel, and means forming a threaded engagement between said second cap and the other end of said mounting whereby said mounting may be secured under tension within said vessel, said second cap being electrically connected with said other contact.

4. In a device of the class described, a pair of contacts adapted to make and break an electrical circuit, means for mounting said contacts in cooperative relationship, a pair of threaded posts projecting from opposite ends of said mounting and electrically connected to said contacts, a vessel surrounding said contacts and having open ends, and conductor caps adapted to close the ends of said vessel and engage said threaded posts whereby said mounting may be rigidly secured within said vessel upon rotation of either of said caps.

In testimony whereof, I have hereunto set my hand.

FREDERICK C. PERREM.
